UNITED STATES PATENT OFFICE

JEREMIAH BINGHAM, OF TOLEDO, OHIO, ASSIGNOR TO THE BINGHAM STAMPING & TOOL COMPANY, OF TOLEDO, OHIO, A CORPORATION OF OHIO.

HUB CONSTRUCTION FOR DISK WHEELS OR THE LIKE.

Application filed November 27, 1925. Serial No. 71,679.

This invention relates to wheels, pulleys, rollers or the like of the disk type, and has primarily for its object the provision of a simple, novel, strong and durable hub construction and hub sleeve mounting for articles of this character.

Other objects and advantages of the invention will be apparent from the following detailed description thereof,

10 While the invention in its broader aspect is capable of embodiment in numerous forms, one embodiment thereof is illustrated in the accompanying drawings which is a central sectional view of a wheel of disk 15 form and of the type commonly used in connection with juvenile vehicles, but is not restricted to such use.

Referring to the drawings, 1 and 2 designate the opposed disks or side portions 20 of the wheel or other article embodying the invention, the central portions of which are spaced apart and each provided with an opening, the edge wall of which is turned outwardly in the present instance to form 25 a cylindrical flange 3.

A cylindrical cup-shaped member 4 of a diameter to fit within the opening formed by the flange 3 of each disk is forced or inserted within such flange and is of a 30 length sufficient for its inner and outer ends to project beyond the respective inner and outer ends of the flange. This enables the inner free end edge of the member 4 to be flanged outwardly, as shown at 5, to engage 35 the inner marginal edge portion of the respective disk. The outer closed end of the member 4, in the present instance is axially compressed to form an annular outwardly offset shoulder or flange 6 around its edge 40 for engagement with the outer end of the flange 3 in opposition to the flange 5. In practice, it is preferable to form the flange 5 on the member 4 before inserting the member in the disk opening and then to assemble 45 the member and disk before securing together the two disks of the wheel. The members 4 are then securely held in the disks by forming the offset flanges 6 on the

outer ends thereof in engagement with the outer ends of the disk flanges 3. 50

An annular ring member 7, which preferably has its opposite edge portions flanged or turned in the same direction and in parallel relation so that the member is of substantially U-form in cross-section, is fitted 55 closely into the cup member 4 with its web or radially disposed portion in flat contact with the closed end portion 8 of the member 4 and with its outer flange opposing the flange 3 of the associated disk. 60

The closed end 8 of the cup member 4 is provided with a central hub sleeve receiving opening 9, which opening corresponds in size to that of the opening of the ring member 7. A hub sleeve 10 has its ends fitted into 65 the central openings of the respective members 4 and 7 and formed with a shoulder 11 in spaced relation to its end for engagement with the free end of the inner flange of the ring member 7 and having an 70 annular outwardly projecting flange or shoulder 12 at its end for engagement with the outer side of the portion 8 of the cup member. It will be understood that the members 4 and 7 are retained in rigid as- 75 sembled relation by the opposed coaction of the sleeve shoulders or flanges 11 and 12 therewith and that the sleeve is also thereby firmly held in rigid relation to the two disks of the wheel or other article with 80 which associated. In order that the flanges 12 of the sleeve may stand in flush relation with the outer sides of the portions 8 of the cup members, the inner marginal edges of the portions 8 are inwardly offset the thick- 85 ness of the metal of the sleeve so as to form countersinks 13 for receiving the respective flanges 12. The inner edge portions of the ring members 7 are also countersunk in the same manner to conform to the offsetting of 90 the cup portions 8 and to enable the radial portions of both the cup member 4 and ring 7 to remain in flush contact with each other throughout their radial lengths.

All of the parts of the hub construction 95 are preferably of sheet metal and the

mounting of the same in the relation shown provides a very strong and durable hub construction for supporting the axle receiving sleeve 10. It is evident that this construction provides a hub part for each disk which is considerably larger in diameter than the hub sleeve 10 and which, therefore, not only gives the wheel hub a strong and durable appearance but also materially reinforces 10 and strengthens the central portion of the disk at its point of connection with the sleeve.

In the assembling of the parts, it is preferable in practice to assemble the members 15 4 and 7 within the disks and to insert the ends of the sleeve 10 within the hub portions of the respective disks before securing the disks together. This having been accomplished, the ends of the sleeve may be flanged 20 at 12 in engagement with the outer sides of the respective cup members 4 so as to assist in retaining the disks in assembled relation and to prevent any outward bulging of the hub portions of the disks with 25 respect to the sleeve.

It is preferable to have the flange portion 6 of the cup members 4, at least at one side of the wheel, extended radially beyond the disk flange 3 so as to form a shoulder with 30 which the open end of the hub cap 14 may be placed in snap or other suitable holding engagement.

I wish it understood that my invention is not limited to any specific construction, arrangement or form of the parts, as it is capable of numerous modifications and changes without departing from the spirit of the 35 claims.

Having thus described my invention, what 40 I claim as new and desire to secure by Letters Patent is:

1. A hub construction for disk wheels having a central opening, comprising a cup member mounted in the opening and secured 45 against axial movements therein, a ring member mounted within the cup member and operating therewith to form a hub sleeve mounting in inwardly spaced relation to the cylindrical portion of the cup member, and a hub sleeve mounted in said cup and ring members.

2. A hub construction for disk wheels having a central opening therein, comprising a hub sleeve disposed centrally in said 55 opening in spaced relation to its wall, a pair of members mounted one within the other in said central opening and firmly carrying and providing a mounting for said sleeve.

3. A hub construction for disk wheels 60 having a central opening with the edge wall of the opening outwardly flanged, comprising a cup member fitted in said flange and secured against axial movements therein, the closed end of the cup member having a central opening in inwardly spaced relation to

the cylindrical portion of the member, a hub sleeve mounted in the opening of the cup member, and a ring member fitting into the cup member and onto the sleeve end to co-operate with the cup member to form a 70 reinforced mounting for the sleeve.

4. A hub construction for disk wheels having a central opening therein, comprising a cup member mounted in said opening and having shouldered engagement with the 75 inner and outer edge walls thereof, said member having its closed end provided with a central opening, a ring member of U-form in cross section fitted into said cup member in opposition to the wall of the disk 80 opening, a hub sleeve having one end fitted in the opening of said cup and ring members and having opposed shouldered engagement therewith to retain said member and the sleeve in assembled relation, and means 85 for supporting the other end of the sleeve.

5. A hub construction for disk wheels having a central opening therein, comprising a cup member mounted in said opening and having shouldered engagement with the 90 inner and outer edge walls thereof, said member having its closed end provided with a central opening, a ring member of U-form in cross section fitted into said cup member in opposition to the wall of the disk opening, a hub sleeve having one end fitted in the opening of said cup and ring members, and having opposed shouldered engagement 95 therewith to retain said members and the sleeve in assembled relation, the outer end of the sleeve being in flush relation to the outer side of the closed end portion of the cup member, and means for supporting the other end of the sleeve.

6. A hub construction for disk wheels having a central opening, comprising a cup member fitted in said opening, and having inner and outer shouldered engagement with the wall thereof, the closed end portion of the cup member having a central opening 105 therein with its marginal edge wall portion inwardly countersunk, a ring member of U-form in cross section fitted in the cylindrical portion of the cup member and having its closed side in abutment with the closed end portion of the cup member around its opening, and the hub sleeve in the openings of said cup and ring members in shouldered engagement with the inner edge of the ring member and having an opposed flange at its 110 end seating within the countersink of the member.

7. A wheel-like article having opposing disks provided with central openings with the edge walls of said openings outwardly flanged, a cup member fitted within the flange of each opening and having shouldered engagement with the inner and outer ends of the respective flanges, each cup member having a central hub sleeve receiving open- 115 120 125 130

ing in its closed end portion, a ring member of U-form in cross-section seated within each cup member and having its sidewall in engagement with the closed end portion of the cup member and having its inner flange forming a continuation of the opening wall of the cup member, and a hub sleeve fitted at each end within the bearings formed by

the respective sets of cup and ring members and in shouldered engagement with the inner and outer edges of the members of each set to retain the parts in rigid assembled relation. 10

In testimony whereof I have hereunto signed my name to this specification.

JEREMIAH BINGHAM.
